UNITED STATES PATENT OFFICE.

JOHN G. MILLHOUSE, OF LITCHFIELD, AND FRED W. SCHNEIDER AND RICHARD FARMER, OF NOKOMIS, ILLINOIS.

SAFETY RAILROAD STOP.

Application filed January 7, 1921, Serial No. 435,735. Renewed November 20, 1922.

To all whom it may concern:

Be it known that we, JOHN G. MILLHOUSE, FRED W. SCHNEIDER, and RICHARD FARMER, citizens of the United States, and residents, 5 respectively, of the city of Litchfield, in the county of Montgomery, in the State of Illinois, and of the city of Nokomis, in the county of Montgomery and State of Illinois (whose post-office addresses are, respectively, 10 Litchfield, Illinois, and Nokomis, Illinois), have invented a new and useful Safety Railroad Stop, of which the following is a specification.

Our invention relates to improvements of 15 railroad car stops and objects of our improvement are to produce a safety railroad car stop that can be readily put in place on the rail and one that can be very easily removed after the car has been stopped by it 20 and one that is simple in design, effective in operation and inexpensive to produce.

We attain these objects by the mechanism illustrated in the accompanying drawing, in which

25 Figure 1 is a vertical cross sectional view of our invention along a line A—B of Figure 3.

Figure 2 is an elevation of our invention in operation stopping a car.

30 Figure 3 is an end view of Figure 2.

Figure 4 is an elevation of our invention showing it in its elevated position by means of which it is removed from the car wheel.

Figure 5 is an end view of Figure 4.

35 Similar numerals refer to similar parts throughout the several views.

In the several views 1 represents the rail, 2 is an I-shaped member having one side of the I registering on the rail and the other 40 side of the I shape extending upwards having the apertures shown, through which passes a pin 3 which is retained in position by the spring cotter pins 4. Journaled on pin 3 is a lever 5 having a handle 6 which 45 can be made long for convenience in lifting. In the forward end of the lever are the apertures shown. In the upper one of these apertures is fastened pin 7 by means of the spring cotter pin 8. Journaled on the 50 ends of the pin 7 is the U-shaped member 9 whose sides are triangular in shape and each of which has notch 10 cut into same which when the device is in position to stop a car register with the pin 3 as shown in 55 Figure 2. Removably fastened to 2 by

means of bolts and nuts 11 is a tongue 12 which when the device is in its stopping position is between the rail and the car wheel 13 as shown in Figure 2.

In operation our safety stop is placed on 60 the rail with the lever handle 6 down as shown in Figure 2 at a point where the car is to be positioned and the car started and pushed toward it, when the wheel 13 will mount the tongue 12 and strike the U-shaped 65 member 9, and thus to move the car any farther it must slide the entire safety stop along the rail which stops the car. To remove the safety stop it is only necessary to put a long pipe on the handle 6 and simply 70 raise it to the position shown in Figure 4 when the U-shaped member 9 acts like a car mover and pushes the car along the tongue and on the track when the safety stop can be removed.

75 It is evident from the above description that our device is very simple and effective in operation and inexpensive to construct and that it can easily be handled by one man.

It will be understood, of course, that while 80 we have here shown one form of our invention we do not want to be limited to the exact form shown, but wish to have it taken in a sense illustrative of any and all forms of our invention as may be set forth in the 85 appended claims.

We claim:-

1. In a safety railroad car stop, a suitably shaped frame having apertures, a projecting member mounted in said frame, which rests 90 on the rail and carries the car wheel, a pin mounted in said apertures, a suitably shaped lever journaled on said pin and a suitably shaped member journaled on said lever co-acting with said frame.

95 2. In a safety railroad car stop, a suitably shaped frame having apertures, a projecting member removably mounted in said frame, which rests on the rail and carries the car wheel, a pin mounted in said apertures, a 100 suitably shaped lever journaled on said pin and a suitably shaped member journaled on said lever co-acting with said frame.

3. In a safety railroad car stop, a suitably shaped frame having apertures, a projecting member mounted in said frame, which rests on the rail and carries the car wheel, a pin mounted in said apertures, a suitably shaped lever journaled on said pin and a suitably 105 shaped member journaled on said lever 110

whose outer end remains in contact with said frame.

4. In a safety railroad car stop, a suitably shaped frame having apertures, a projecting member removably mounted in said frame which rests on the rail and carries the car wheel, a pin mounted in said apertures, a suitably shaped lever journaled on said pin and a suitably shaped member journaled on 10 said lever whose outer end remains in contact with said frame.

5. In a safety railroad car stop, a member having apertures which register with rail, a projection from said member which registers with the car wheel tread, a pin mounted in said apertures, a suitably shaped lever journaled on said pin and a suitably shaped

member journaled on said lever which member contacts with said frame.

6. In a removal safety railroad car stop, a lever having two apertures, a frame having apertures, a pin journaled in one of said apertures in said lever and the apertures of said frame, a suitably shaped member having apertures slidably mounted on said frame, and a pin journaled in the apertures of said lever and the apertures of said suitably shaped member.

JOHN G. MILLHOUSE.

F. W. SCHNEIDER.

RICHARD FARMER.
